UNITED STATES PATENT OFFICE.

ELEAZER GALE BURLINGAME, OF DETROIT, MICHIGAN.

DESIGN FOR A PAIR OF SPECTACLES.

49,948.

Specification for Design.

Patented Nov. 28, 1916.

Application filed August 12, 1916. Serial No. 114,650. Term of patent 7 years.

To all whom it may concern:

Be it known that I, ELEAZER GALE BURLINGAME, a citizen of the United States, residing at Detroit, in the county of Wayne and State of Michigan, have invented a new, original, and ornamental Design for Spectacles, of which the following is a specification, reference being had therein to the accompanying drawing, forming part thereof.

The figure is a front elevation of the spectacles.

I claim:

The ornamental design for a pair of spectacles, as shown.

ELEAZER GALE BURLINGAME.

Witnesses:

G. E. McGRAFF,
KARL H. BUTLER.
